**COMBINED RECORD AND PLAYBACK HEAD FOR
A MAGNETIC TAPE RECORDER OR SIMILAR
ARTICLE**

**Paul H. Schulte, D-9 Gardenia, San Francisco, Urb.,
Rio Piedras, Puerto Rico**

Filed Nov. 1, 1963, Ser. No. 77,253

Term of patent 3½ years

(Cl. D26—14)

FIG. 1

FIG. 2

FIG. 3

FIG. 4

FIG. 5

FIG. 1 is a perspective view of a combined record and playback head for a magnetic tape recorder or similar article, showing my new design;

FIG. 2 is a top plan view;

FIG. 3 is a front elevational view, the rear being substantially a mirror image thereof;

FIG. 4 is a side elevational view, the opposite side being substantially a mirror image thereof; and

FIG. 5 is a bottom plan view thereof.

I claim:

The ornamental design for a combined record and playback head for a magnetic tape recorder or similar article, substantially as shown and described.
